UNITED STATES PATENT OFFICE.

OTIS K. NEWELL, OF BOSTON, MASSACHUSETTS.

NURSING-BOTTLE.

SPECIFICATION forming part of Letters Patent No. 466,361, dated January 5, 1892.

Application filed October 23, 1891. Serial No. 409,592. (No model.)

To all whom it may concern:

Be it known that I, OTIS K. NEWELL, residing in Boston, county of Suffolk, and State of Massachusetts, have invented an Improvement in Nursing-Bottles, of which the following description, in connection with the accompanying drawings, is a specification, like letters and figures on the drawings representing like parts.

10 This invention relates to vented nursing bottles, and has for its object to provide the same with a more efficient covering for the vent.

Prior to my invention I am aware that 15 vented nursing-bottles have been provided with a covering for the vent, consisting of an annular rubber band encircling the bottle near its bottom, the said band being fitted into an annular groove in the bottle. A vent- 20 ed nursing-bottle constructed as described is objectionable, owing to the liability of the band becoming readily detached from the bottle.

My present invention has for its object to 25 provide a vented nursing-bottle with a covering for the vent, which is firmly secured on the bottle and may be moved to uncover the vent without becoming detached from the bottle.

30 In accordance with my invention the vent-covering is composed of a yoke or annular ring encircling the neck of the bottle, and a band secured to or forming part of the said yoke and passed under the bottom of the bottle.

The nursing-bottle is preferably made substantially pear-shaped, so that when laid on its side, as when the baby is nursing lying down, the mouth of the bottle is thrown toward 35 the mouth of the baby rather than away from it.

The particular features of my invention will be pointed out in the claims at the end of this specification.

45 Figure 1 is an elevation of a vented nursing-bottle embodying my invention, the bottle being shown in its upright position. Fig. 2 represents the nursing-bottle shown in Fig. 1 as laid upon its side; Fig. 3, a detail of the 50 vent-covering preferred by me; and Fig. 4 is an elevation of the nursing-bottle provided with a modified form of covering.

The nursing-bottle A, preferably made pear-shaped, as herein shown, and also preferably composed of annealed glass, is provided near 55 its bottom with a vent-opening a. The bottle A is provided with my improved form of vent-covering, preferably made in the shape shown in Fig. 3, it consisting of an annular band a', provided with an enlargement for a portion 60 of its length, as at a², the latter being provided with a slit a³, through which the neck of the bottle is inserted when the band is fitted to the bottle. The slotted enlargement a² when separated, as when fitted upon the 65 bottle, forms a yoke composed of two members 2 3, united by the band a', which is passed down the length of the bottle and under the bottom of the same, the band a', when in position, normally covering the vent a. 70 The rubber band is enlarged, as at a², so that when slotted the members 2 3 will be of substantially the same width as the band a', so as to obtain the desired or necessary strength at the yoke. 75

I prefer to make the vent-covering as a single band having an enlargement provided with the slit a³; but I do not desire to limit myself in this respect, as it is evident the main portion of the band a' may be made 80 separated from the yoke portion, as shown in Fig. 4, the said yoke being shown in the said figure as an annular ring b, provided with lugs or ears b', to which the ends of the band a' may be secured in any suitable or desired 85 manner—as, for instance, by inserting the ears or lugs b' through suitable openings in the ends of the band. I prefer to make the nursing-bottle A pear-shaped, as herein shown, so that when the bottle is laid upon its side, 90 as represented in Fig. 2—as, for instance, when laid upon the breast of the baby in the act of nursing in a recumbent position—the mouth of the bottle will be thrown toward the mouth of the baby rather than away from it, 95 thereby assisting in the efforts of the baby to nurse, as the nipple is naturally inclined toward the baby's mouth.

When the bottle is not to be used, the band a' normally covers the vent-opening a; but 100 when it is desired to vent the bottle the band a' may be pushed aside by the finger, so as to uncover the vent a, and care need not be exercised as to the amount to which the band

a' is moved from the vent, as the said band may be removed entirely from under the bottle, but will be retained on the bottle by means of the yoke encircling the neck of the 5 bottle. In this manner the vent-covering band is retained on the bottle and liability of misplacing and losing the same is avoided.

By reason of the pear shape of the bottle the vent *a*, when the bottle is in position for 10 nursing, is at the highest point, thereby avoiding leakage.

I claim—

1. The combination, with a nursing-bottle provided with a vent-opening, of a vent-covering consisting of a yoke encircling the neck of the bottle, and a band *a'*, passed under the 15

bottom of the bottle to normally cover the vent therein, substantially as described.

2. The combination, with a nursing-bottle provided with a vent-opening *a*, of a vent-covering consisting of a band *a'*, passing under the bottom of the bottle, and a yoke integral with the band and fitted upon the neck of the bottle, substantially as described.

In testimony whereof I have signed my 25 name to this specification in the presence of two subscribing witnesses.

OTIS K. NEWELL.
